UNITED STATES PATENT OFFICE.

SAMUEL HICKOK, OF BUFFALO, NEW YORK.

CAR-COUPING TOOL.

SPECIFICATION forming part of Letters Patent No. 236,156, dated January 4, 1881.

Application filed June 28, 1880. (No model.)

To all whom it may concern:

Be it known that I, SAMUEL HICKOK, of Buffalo, in the county of Erie and State of New York, have invented certain new and useful 5 Improvements in Car-Coupling Tools; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to a device for handling car-coupling links in the act of coupling 15 cars together without the operator standing between the cars; and the novelty consists in the construction and adaptation of the implement for that purpose, as will be more fully hereinafter set forth, and specifically pointed 20 out in the claims.

For the successful manipulation of the link in coupling cars together, so as to have the link enter the jaw of the draw-head, not only must the link be lifted or depressed, but in 25 many cases it must be pulled or pushed forcibly to or from the operator, or, in other words, must be forced transversely. In order to do this efficiently the implement must be capable of seizing the link between devices that will 30 lock it in either direction and allow both vertical and transverse motions. To accomplish this end various devices have been produced—such, for instance, as spring-jaws, which, while they may allow a slight manipulation of the 35 link, can only lift the link by the main force of the operator, and are not adapted to pull the link forcibly toward the operator, for the reason that the spring-jaws would open and release the same. Rigid jaws have also been 40 used; but these have been only efficient with a twisting or rotary motion of the implement in either direction, and possibly to push away from the operator; but to forcibly and quickly pull the link toward the operator they were 45 not reliable, as the amount of friction necessary to hold the link against a smooth jaw could not always be determined, and wear by such friction made it still more unreliable. To

avoid these difficulties, and to provide a perfect and reliable lock to the implement upon 50 the link, this invention is designed.

In carrying out my invention I employ a shank of sufficient length, having upon one end a transverse handle to give great rotary power to the device, and upon the other end curved 55 transverse arms, which, at a proper distance from the plane of the shank, assume a form parallel to said plane. One of these jaws is made longer than the other, enabling the operator to press the upper or inner side of this 60 long jaw against the upper or under surface of the link, and then, by pushing the implement and rotating it slightly, insures a proper and certain hold. I also provide the inner surface of the jaws, upon each side, with a bevel, which, 65 acting upon a similar bevel upon the locking arms or lugs, serves as a steady bearing for the link, and assists materially in the efficient operation of the implement.

In the accompanying drawings, Figure 1 is 70 a perspective view; Fig. 2, a detail, and Fig. 3 a perspective view of the implement complete.

Referring to the drawings, A represents the shank, and B the handle.

C represents the elongated jaw, having trans- 75 verse lugs c, and D the opposite jaw, having the transverse lugs d. The jaw C has an extension, H, for purposes described, and is adapted to pass beneath the link x until a sure bite is obtained, when the link is guided into 80 the mouth of the draw-head x'.

J represents the bevel which is upon both sides of the inner surfaces of the jaws, and extends from the outer point of either of the lugs c to the same point on the opposite lug, d. 85

I deem the bevel J of great importance in this device, and also the arrangement by which the lugs c d are opposite each other, whereby not only is a perfect and reliable lock upon the link obtained, but a large and firm bearing-surface provided whichever way the implement is rotated.

What I claim as my invention is—

1. The handle provided with arms, having transverse lugs arranged opposite each other 95 to form a gripping or locking tool, by which

the coupling-link can be firmly held and forcibly moved in any direction, substantially as and for the purposes set forth.

2. The handle A B, having arm C, with extension H and lugs c, and having arm D, with lugs d, said lugs being opposite to each other, as specified, for the purposes set forth.

3. The handle A B, having arms C D, said arms provided with transverse lugs c d, the

extension H, and the incline J upon each side 10 of the inner surface of the jaws, and extending from lug to lug, as specified.

In testimony that I claim the foregoing I have hereunto set my hand.

SAML. HICKOK.
